UNITED STATES PATENT OFFICE.

CHRISTOPHER D. FINDLAY AND DAVID D. CRAIG, OF MACON, GEORGIA.

IMPROVEMENT IN HAY AND COTTON PRESSES.

Specification forming part of Letters Patent No. 150,313, dated April 28, 1874; application filed March 16, 1874.

To all whom it may concern:

Be it known that we, CHRISTOPHER D. FINDLAY and DAVID D. CRAIG, of Macon, in the county of Bibb and State of Georgia, have invented a new and Improved Press for Hay, Cotton, &c.; and we do hereby declare that the following is a full, clear, and exact description of the same, reference being had to the accompanying drawing, forming a part of this specification, in which—

Figure 1 is a side elevation, partly broken away; Fig. 2, a vertical section; Fig. 3, a plan view; Fig. 4, a detail side view of ring.

The invention relates to hay, cotton, or other presses, but is intended more particularly as an improvement upon the press for which Letters Patent were granted to us February 21, 1871.

The invention will first be fully described, in connection with all that is necessary to a full understanding thereof, and then pointed out in the claim.

A represents the follower-screw, having rounded spiral groove or thread, and attached to a plate, B, to the opposite side of which the follower is rigidly connected. C is a rotary nut, placed within a plain fixed tube, B', and having small recesses, c, in which are balls a, (made of any suitable material,) and arranged in a spiral order to correspond with thread of screw A. This is employed instead of the spirally slotted and grooved circumjacent tube of our former patent, the nut C being thus thickened and strengthened, while the frictional contact is lessened, and the resistance greatly diminished. The tube or nut C has a flange, C', at its lower end, and in the upper face of this flange a concavity whose bottom is inclined upwardly from the circumference to

the nut C. Above this flange, and between it and the flange b' of tube B', is located a ring, D, which is constructed with the top aperture d and open side slots d' in the pendant flanges D D'. E is a series of conical rollers, having their journals e placed in the notches or open side slots d' d', and protruding upwardly through the apertures d, and against the flange b' of outer fixed tube B'. The friction-rolls E increasing in diameter and circumference as they recede from the rotary nut C will thus avoid the unequal pressure upon the perimeters of our former rollers, induce a more perfect uniformity thereof, and thus decrease the frictional resistance to the rotation of the nut. H is a wrench or lever head, having a median recess to fit over the angular neck of nut C, and thus enable it to be rotated. This head H is fastened so that it cannot rise by pins F F, that pass through holes h, and into grooves c' of said neck.

Having thus described our invention, what we claim is—

The nut C, having a series of recesses, c, formed in its inner surface, and provided at its lower end with a flange, C', having its upper surface inclined upwardly from near the circumference to the nut, in combination with a series of balls, a, screw A, conical rollers E, and flanged tube B', all constructed substantially as and for the purpose specified.

CHRISTOPHER D. FINDLAY.

DAVID D. CRAIG.
